UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

SWITCH-CONTROLLING SYSTEM.

1,334,105.

Specification of Letters Patent. Patented Mar. 16, 1920.

Application filed June 21, 1916. Serial No. 105,002.

To all whom it may concern:

Be it known that I, ALBEN E. LUNDELL, a citizen of the United States, residing at New York, in the county of Bronx and State of New York, have invented certain new and useful Improvements in Switch-Controlling Systems, of which the following is a full, clear, concise, and exact description.

This invention relates to a circuit arrangement for controlling the operation of an automatic switch, and more particularly to a circuit arrangement whereby the speed of a brush-driven shaft is made to take place at a uniform desired rate, under the control of an electromagnetic device.

This invention is specially adapted for use with a switch of the structure shown in Patent No. 1,247,399, granted November 20, 1917, to C. J. Hendrickson. This invention is not, however, restricted to use with this particular structure, but may be used to govern the speed of any desired type of switch.

In a switch of the type disclosed in the above mentioned application, motion is applied to a brush shaft through the action of solenoids and plungers. Rotary motion is given to the shaft by the action of a toothed rack on a pinion carried by the shaft, the toothed rack carrying on one end a plunger operated by a solenoid. Vertical motion is obtained by the pull exerted on a plunger mounted directly on the brush-carrying shaft by a second solenoid.

The principal feature of the invention is the provision of means for placing the driving circuit of the shaft actuating magnet under the control of an electro-magnetic speed-controlling device.

In a preferred embodiment of the invention, the arrangement is as follows: at the end of the first half of each step, a slow-release relay is actuated, and upon the completion of each full step, the driving circuit is maintained open until the relay releases its armature. This necessitates a time interval between successive steps and insures a uniform rate of advancement of the brush shaft.

Referring to the drawings, Figure 1 is a side elevation of a switch suitable for use with this invention; Fig. 2 is a plan view, partly in section, of the same, on the line

2-2 of Fig. 1; Fig. 3 is a circuit arrangement embodying the invention.

55

Since the invention is not limited to a particular mechanical structure, only so much of the mechanism shown in Figs. 1 and 2 will be described as is necessary to an understanding of the invention.

60

The switch shown is of the "around-and-up" type. A solenoid 1 is arranged to operate a plunger 2, such plunger carrying a strip of toothed rack 3. This toothed rack is in engagement with a pinion 4 mounted on the rotatable shaft 5. The action of this solenoid imparts rotary motion to the shaft. Vertical motion is given to the shaft by a second solenoid 6, which is arranged to operate a plunger 7 mounted in the shaft 5.

70

A frame 8, pivotally and slidably mounted on studs 9 and 10, carries at one end an armature 11, and at its other end, a pawl 12 which is arranged to engage the teeth of the rack 3 and is normally held from engagement therewith by the action of a spring 13.

75

A similar frame 14 is provided for solenoid 6 and is also pivotally and slidably mounted on studs 15 and 16. This frame carries an armature 17 and a pawl 18, which is arranged to engage notches 19 on the brush shaft.

80

Side-switch wipers 20 are arranged to swing over contact sets 21. A ratchet wheel 22 and hinged escapement 23 supply means for electromagnetic control.

85

Spirally disposed brushes 24 are arranged about the shaft 5, and may be brought into an operative position with relation to their respective groups of terminal sets 25, 26, by 90 the rotation of said shaft.

Circuit controlling means are indicated at 38 and 39. An arm 63, carrying an anti-friction roller 64, is arranged to successively ride over circular teeth 38, thereby alternately operating contacts 61 and 62 for a purpose to be described later.

95

A magnet 27 controls the release of the entire switch. A pivoted armature lever 28 is actuated when magnet 27 is energized, and 100 restores the side switch by engaging a lug 29 on the toothed segment 22, the other end of the lever 28 being arranged to engage an offset 30 on a pivoted bell crank lever 31 to withdraw a holding pawl 32 from engagement with the toothed rack 3. This

105

pawl is normally spring-pressed into engagement with the toothed rack by spring 33. The lever 31 in operating carries with it an arm 34 attached to frame 14, causing the withdrawal of pawl 18 from a slot 19, the brush shaft now being free to return to normal, being restored vertically by the action of gravity, and in a rotary direction by the retraction of the toothed rack by the action of springs 35 and 36.

The solenoids are made subject to impulse control in the following manner, the control mechanism for the rotary solenoid only being described, since the operation of the vertical controlling means is the same: upon the energization of the solenoid 1, the armature 11 is attracted and throws the pawl 12 into engagement with one of the teeth of the rack 3. Upon attraction of plunger 2, the pawl 12 slips into a notch between adjacent teeth of the rack 3, so that the rack carries with it the bracket 8. The motion of the rack is limited to one step, since the armature 11 acts as a stop when it engages the head of solenoid 1. Upon the termination of current flow through the solenoid, the armature 11 is retracted by the action of spring 13, thus disengaging the pawl 12 from the toothed rack. The bracket 8 is then returned to its normal position under the influence of a spring 37, the spacing of the teeth on the rack being such that the pawl 12 now lies in the plane of the next tooth and is ready for engagement therewith on the next energization of the solenoid 1.

Referring now to the circuit arrangement shown in Fig. 3, a selector circuit is shown, connection being extended thereto from the substation at the left through a line finder switch or similar device whose brush set and terminals are shown at 40. A connector is diagrammatically shown at 70. The subscriber's receiver being off the hook, a line relay 41 is energized over the following circuit; free pole of battery, left-hand winding of relay 41, through the finder 40, the loop of the calling subscriber, and right-hand winding of relay 41, to ground. Relay 41 is energized and closes a circuit for slow-release relay 42 from free pole of battery, winding of relay 42, armature and front contact of relay 41, to ground. Relay 42 pulls up and breaks the circuit of release magnet 27, which would otherwise be closed after the brush shaft has made its first movement.

The subscriber now sends a series of impulses to position a brush set below a selected group of trunks leading to connectors in the desired group. Upon each retraction of the armature of relay 41, an impulse is sent through rotary solenoid 45 from free pole of battery, winding of solenoid 45, side-switch arm 46 and its first contact, armature and front contact of relay 42, armature and line is advanced to a connector 70, through

parallel with solenoid 45, slow-release relay 44 is energized. While the impulses are being sent, relays 42 and 44 hold up their armatures, being slow to release. Escape magnet 51 is energized upon the operation of relay 44. At the conclusion of the sending of impulses, relay 41 remains energized, and relay 44, after a time, is deenergized. The retraction of the armature of relay 44 opens the circuit of magnet 51, which deenergizes and releases the side-switch arms into their second position.

In the second position of the side switch, current is led to the vertical solenoid 52 through free pole of battery, winding of solenoid 52, side-switch arm 50 and its second contact, armature and back contact of slow-release relay 53, contacts 62 and 39, to ground. The solenoid 52 is energized and moves the brush shaft a half step, at which time the roller 64 rides up on one of the teeth 28, breaking the circuit of solenoid 52 and completing the circuit for relay 53 from free pole of battery, and contacts 61 and 39, to ground. Relay 53 at once is energized and the circuit of solenoid 52 is again completed from grounded battery, winding of solenoid 52, side-switch arm 50 and its second contact, armature and front contact of relay 53, and contacts 61 and 39, to ground. The shaft is again moved a half step, at which time the roller 64 drops into one of the notches 65, thereby opening the circuits of solenoid 52 and relay 53. Relay 53 after a lapse of time releases its armature, again completing the circuit of solenoid 52 over the path first described. This mode of operation continues until a brush set 60 finds the terminals of an idle trunk, the time interval required after each step for the release of relay 53 preventing the shaft from operating at undesirable speed.

The escape magnet 51 is maintained energized in the second position of the side switch by a circuit from free pole of battery, winding of magnet 51, side-switch arm 47 and its second contact, to ground through the contact 66, which is closed until the shaft makes its first vertical step. Assuming that a busy condition of trunks is indicated by ground on the test terminals 67 over which the test brush 68 passes, and that an idle condition of trunks is indicated by the absence of ground on such terminals, the escape magnet is maintained energized during the hunting operation, since the test brush 68 bridges the successive terminals and maintains circuit through escape magnet 51, to ground. When the test contact of an idle trunk is encountered, escape magnet 51 is deenergized and releases the side switch into third position. In position 3 of the side switch, the circuit of the vertical stepping solenoid 52 is opened, and the subscriber's back contact of relay 41, to ground. In par-

side-switch arms 48 and 49 and the brushes and terminals of the selector as indicated at 60. The connection to the wanted subscriber through the connector 70 may be made in any well-known manner.

At conclusion of the conversation, the relay 41 is deenergized when the calling subscriber hangs up his receiver. This opens the circuit of relay 42, which, after a time, releases its armature and completes the circuit of release magnet 27 from grounded battery, winding of relay 27, off-normal contact 69, armature and back contact of relay 42, and armature and back contact of relay 41, to ground. This circuit is maintained until the switch is fully restored, in the manner previously described, at which time off-normal contact 69 is opened and the release magnet deenergized.

What is claimed is:

1. In a telephone exchange system, incoming lines, outgoing multiple trunks, selector switches for interconnecting said lines and trunks, said trunks appearing in each of said selectors, a solenoid for moving one of said selectors, a circuit for actuating said solenoid, means for intermittently interrupting said circuit at one point to maintain the speed of movement of said selector uniform, and a test magnet for permanently interrupting said circuit at another point when the first idle trunk is reached.

2. A line selecting switch comprising movable terminals, an operating solenoid therefor, and means including a slow-release relay for maintaining uniform speed of operation of said terminals.

3. In a line selecting switch comprising movable terminals, an operating electromagnetic device therefor, a driving circuit, an interrupter actuated in response to motion of said terminals, and means, including a slow-release relay, for maintaining uniform speed of operation of said terminals under the control of said interrupter.

4. A line selecting switch comprising movable terminals, an operating solenoid therefor, a driving circuit for said solenoid, a slow-release relay, and means for interrupting said driving circuit between successive steps of said switch until the release of said slow-release relay, thereby necessitating a time interval between successive steps.

5. A line selecting switch including a brush-carrying shaft, electromagnetic means for imparting motion to said shaft, a driving circuit therefor, a slow-release relay, contact springs operated in accordance with the successive positions of said shaft, said contact springs shifting the control of the driving circuit to said slow-release relay at the completion of the first half of each step, the driving circuit being interrupted at the completion of each full step until said relay releases its armature.

6. A line selecting switch including a brush-carrying shaft, a series of notches on said shaft, electromagnetic means for imparting motion to said shaft, a driving circuit therefor, a member carrying a roller 70 which travels over said notches, contact springs operated thereby, a slow-release relay, said contact springs shifting the control of said driving circuit to said slow-release relay at the completion of the first half of 75 each step, the driving circuit being interrupted at the completion of each full step until said relay releases its armature.

7. A line selecting switch including a brush-carrying shaft, means for imparting motion to said shaft, a driving circuit therefor, a slow-release relay, contact springs operated in accordance with the successive positions of said shaft, said contact springs shifting the control of the driving circuit to 85 said slow-release relay at the completion of the first half of each step, the driving circuit being interrupted at the completion of each full step until said relay releases its armature.

8. A line selecting switch including a brush-carrying shaft, an operating solenoid therefor, a driving circuit for said solenoid, a series of notches on said shaft, a member carrying a roller traveling over said notches, contact springs operated by said member, a slow-release relay said contact springs shifting the control of said driving circuit to said slow-release relay at the completion of the first half of each step, the driving circuit being interrupted at the 100 completion of each full step until said relay releases its armature.

9. In a telephone exchange system, incoming lines and outgoing lines, a selector switch for interconnecting said lines, said switch including a brush-carrying shaft, a solenoid responsive to impulse control for imparting primary motion to said shaft, a second solenoid for imparting secondary motion to said shaft, and means including a slow-release relay for controlling the speed of operation of said switch.

10. In a telephone exchange system, incoming lines and outgoing lines, a selector switch for interconnecting said lines, said switch including a brush-carrying shaft, a solenoid responsive to impulse control for imparting primary motion to said shaft, a second solenoid for imparting secondary motion to said shaft, a driving circuit for said secondary solenoid, a slow-release relay, and means for interrupting said driving circuit between successive steps of said switch until the release of said relay, thereby necessitating a time interval between successive steps.

11. In a telephone exchange system, incoming lines and outgoing lines, a selector switch for interconnecting said lines, said

70

- switch including a brush-carrying shaft, a solenoid responsive to impulse control for imparting primary motion to said shaft, a second solenoid for imparting secondary motion to said shaft, a driving circuit therefore, a slow-release relay, contact springs operated in accordance with the successive secondary positions of said shaft, said contact spring shifting the control of said driving circuit to said slow-release relay at the conclusion of the first half of each step, the driving circuit being interrupted at the completion of each full step until said relay releases its armature.
12. In a telephone exchange system, incoming lines and outgoing lines, a selector switch for interconnecting said lines, said switch including a brush-carrying shaft, a

series of notches on said shaft, a solenoid responsive to impulse control for imparting primary motion to said shaft, a second solenoid for imparting secondary motion to said shaft, a driving circuit for said secondary solenoid, a member carrying a roller traveling over said notches on secondary movement of said shaft, contact springs operated by said member, a slow-release relay, said contact springs shifting the control of said driving circuit to said slow-release relay at the completion of the first half of each step, the driving circuit being interrupted at the completion of each full step until said relay releases its armature.

In witness whereof I hereunto subscribe my name this 20th day of June A. D., 1916

ALBEN E. LUNDELL.
